(57) **CLAIM**

The ornamental design for a clip for a cord management system, as shown and described.

DESCRIPTION

The present application relates to the following Patents and Applications:

to U.S. utility patent application Ser. No. 12/761,326 filed Apr. 15, 2010, entitled Cord Management System,

to U.S. design Pat. No. D636,659, filed Aug. 27, 2010, entitled Strap for a Cord Management System,

to U.S. design patent application Ser. No. 29/368,755 filed Aug. 27, 2010, also entitled Strap for a Cord Management System,

to U.S. design application Ser. No. 29/388,372 filed Mar. 28, 2011, also entitled Strap for a Cord Management System,

to U.S. design application Ser. No. 29/401,643 filed Sep. 13, 2011, entitled Strap with Hook and Loop Closure for a Cord Management System,

to U.S. design application Ser. No. 29/401,359 filed Sep. 11, 2011, entitled Strap with Cord Attachment Mechanism for a Cord Management System, and

to U.S. design application Ser. No. 29/401,930 filed Sep. 16, 2011, entitled Strap with Cord Attachment Mechanism and Hook and Loop Closure for a Cord Management System.

FIG. 1 is a perspective view of an embodiment of our new design of a clip for a cord management system.

FIG. 2 is a view of a first side of the embodiment of FIG. 1.

FIG. 3 is a view of a second side of the embodiment of FIG. 1.

FIG. 4 is a view of a third side of the embodiment of FIG. 1.

FIG. 5 is a view of a fourth side of the embodiment of FIG. 1.

FIG. 6 is a view of a fifth side of the embodiment of FIG. 1.

FIG. 7 is a view of a sixth side of the embodiment of FIG. 1; and,

FIG. 8 is another perspective view of the embodiment of FIG. 1 provided for illustrative purposes, the perspective view illustrating the embodiment when used in conjunction with an object.

The broken lines showing elements of the clip for a cord management system in the above described figures are for illustrative purposes only and form no part of the claimed design.
